UNITED STATES PATENT OFFICE.

KENNEDY DOUGAN, OF MINNEAPOLIS, MINNESOTA.

SUBMARINE ARTILLERY.

1,303,266.

Specification of Letters Patent. Patented May 13, 1919.

Application filed June 8, 1915. Serial No. 32,827.

To all whom it may concern:

Be it known that I, KENNEDY DOUGAN, a citizen of the United States, residing at Minneapolis, in the county of Hennepin and State of Minnesota, have invented certain new and useful Improvements in Submarine Artillery, of which the following is a specification.

My invention relates to submarine artillery and has for its object to provide a submarine war vessel with a gun of very large caliber embodying the general principles of my co-pending application, Serial Number 23,869, filed April 26, 1915, in which the projectile is driven from one end of the gun and an inertia charge in the opposite direction from the other end of the gun, thereby balancing the explosion and preventing recoil.

In the embodiments of my invention hereinafter disclosed and claimed, I provide means for mounting one or more guns upon a submarine so as to swing about a pivotal support for securing the gun adjacent its center.

In this manner the gun may be positioned so that one end will extend above the water-line when the submarine is submerged, the other end of the gun pointing downward in the water. Means are provided for placing the interior of the gun into communication with a loading chamber in the submarine and for withdrawing water from the gun and for cleaning and loading the gun when in such position.

It will be apparent that with a heavy gun of the character herein specified a submarine may approach close to land fortifications, avoiding the war ships and other means of defense, and may throw very large and destructive shells upon the forts at comparatively short range or may lie out to sea beyond the range of coast or harbor defense guns and drop shells into cities or fortifications not within the range of the guns now in use on battle-ships, since the angle of elevation possible is less than half that of the gun herein described, such cities and fortifications thus being quickly reduced. Such a vessel could also get within easy and certain gun-fire range of battle-ships and other war vessels which would thus be destroyed without subjecting the submarine to any danger whatever, thus distinguishing from torpedo warfare in which the range is necessarily so short that the submarine is greatly endangered every time it approaches

close enough to a war vessel to launch effectively a torpedo.

The full objects and advantages of my invention will appear in connection with the detailed description thereof and are particularly pointed out in the claims.

In the drawings, illustrating the application of my invention in one form,

Figure 1 is a plan view and Fig. 2 a vertical central section of a submarine having my improved arrangement applied thereto. Fig. 3 is a front end view of the parts shown in Fig. 1. Fig. 4 is a sectional plan detail of one end of the submarine body shown in Fig. 1. Figs. 5 and 6 are plan and central vertical sections of another form of submarine showing my improvements applied thereto. Figs. 7 and 8 are plan and central sections of a third form of submarine. Figs. 9 and 10 are plan and side elevation views of a submarine having my improvements applied thereto in which a gun appears on each side of the submarine body. Fig. 11 is a longitudinal vertical section through a portion of the center of the submarine shown in Fig. 1 drawn to a larger scale. Fig. 12 is a vertical end section taken on line 12—12 of Fig. 2. Fig. 13 is a vertical end section taken on line 13—13 of Fig. 2. Fig. 14 is a plan section of the submarine shown in Figs. 1 and 2 showing the construction of the trunnion. Fig. 15 is a plan view of the loading mechanism with parts in section. Fig. 16 is a plan view of some of the parts shown in Fig. 15. Fig. 17 is an end elevational view of the loading mechanism. Fig. 18 is a section of the gun through the trunnions showing how the ignition wires are carried from the gun to the point of ignition. Fig. 19 is a view of a sectional plunger. Fig. 20 is a fragmental section of the powder charge showing the method of making contact for ignition. Figs. 21 and 22 are side and end views of a modified contact plug similar to that shown in Fig. 20. Fig. 23 is a view showing the means to prevent water from entering the gun by way of the muzzle.

As illustrated and described, the gun, of the type shown and claimed in my co-pending application aforesaid, is pivotally connected with the body of the submarine so as to extend outside the same and be submerged in the water, the gun being preferably connected in the central horizontal plane of the submarine. The submarine may be spe-

cially constructed to carry my gun. Thus, as shown in Figs. 1 to 4, inclusive, a pair of cigar-shaped submarine bodies 25 and 26 are united by tubular members 27 and 29, 5 all coming to a common point as indicated at 28. The gun 30 is mounted upon a bar 31 which extends across the two members 25, 26 in the horizontal central plane thereof, said gun occupying a space 32 between 10 the members 27 and 29. As shown in Fig. 1 the gun is in alinement with these members, in which position it is adapted for loading. This is the preferred form.

In the form shown in Figs. 5 and 6, a single cigar-shaped submarine body 33 is provided having fore-and-aft slots 34, 35 extending in opposite directions along the central vertical plane of the submarine and the gun 30 is pivoted to the central shaft 36 so 15 that the opposite ends thereof operate in the respective slots, the gun being capable of being horizontally positioned, as indicated in Fig. 6. Steadyng wings 37 and rudders 38 are shown in connection with all of the 20 different forms of submarine.

The form of submarine shown in Figs. 7 and 8 is a desirable form for some purposes comprising a pair of cigar-shaped members 39, 40 secured together fore-and-aft by 25 hollow spacing members 41, 42, which, as will later be pointed out, are adapted to serve as a means of communication with the interior of the gun for loading and cleaning the same. This, of course, is also true of 30 the tubular connectors 27, 29 of Figs. 1 to 4 and the shouldered portions 43, 44 of the form shown in Figs. 5 and 6.

In Figs. 9 and 10 is shown a submarine having a single cigar-shaped body 45 with 40 a pair of guns 30 secured at the centers thereof at each side of the submarine body and adapted to register at their ends with projecting portions 46 in the central horizontal plane of the submarine through which 45 loading and cleaning of the gun is effected.

It is obvious that whichever form of submarine body the gun is applied to, the principle is the same, namely, the provision of a gun of large caliber open at both ends and 50 having a bore extending through the same, said gun being pivotally connected adjacent its center to the submarine so as to be bodily outside of a side portion of the shell of the submarine and being adapted to be oscillated upon that pivot so that one end of the gun will project above the surface of the water when the submarine is submerged, the other end of the gun pointing downwardly into the water. This position is for 55 firing, and the gun will be reactionless as far as the submarine is concerned because the charge of water driven from the submerged end of the gun against the body of water behind the gun will absorb all of the 60 reaction of the explosion which drives the

projectile in the opposite direction. It will also be apparent that in each of the forms shown equivalent means are provided for placing the interior of the gun in communication with the interior of the submarine 70 for loading and cleaning. The features relating to mounting, loading, cleaning and operating the gun, which will now be described and which are illustrated in detail, are properly common to all of the different 75 forms of submarines shown.

At the time of firing such a gun with the lower end extended in the water the pressure to which the barrel is subjected beneath the water will be relatively greater near the end 80 of the barrel than would be the case where the gun is fired into the open air. It may therefore be desirable to make the breech end of the gun which is in the water at the time of firing of greater thickness toward 85 its end than the muzzle end which extends into the air when the gun is fired.

Referring to Figs. 11 to 14, inclusive, it will be noted that the twin submarine shells of Figs. 1 or 7 are substantially cylindrical 90 in cross section and are rigidly secured in parallel alinement by the chamber portions 27, 29, of Fig. 1 or 41, 42 of Fig. 7. The interior of such connecting members provides chambers which are designated generally by the reference numerals 47 and 49, and an opening 48 will be provided from the interior of the submarine shells into such chamber. Within these chambers is mounted the means for obtaining communication with the interior of the gun for loading, cleaning, etc., which will now be described.

Referring particularly to Figs. 15 and 16, the end walls 50 and 51 of chambers 49 and 105 47, respectively, are provided with an opening surrounded by an inwardly-extended cylindrical bushing member 52 secured to castings 53 to the respective end walls. The bushing member 52 is provided with an inwardly-turned circular flange 54 which has a circular opening of less diameter than the remainder of the bushing member, and slideable in this opening is a cylindrical plug 55 which is held in water-tight relation to the bushing member 52 by means of packing 56 and a packing ring 57, as clearly shown in Fig. 15. An extension 59, rigidly connected with plug member 55, has thereon a gate 60 controlled by a hand wheel 61 for sealing 110 the inner open end 58 of the interior of plug member 55. The ends 62 of the gun 30 are internally rounded as indicated at 63 in Fig. 15, and the plug member 55 has a correspondingly spherical portion 64. When 115 it is desired to place the gun into communication with chambers 47 and 49 the plug members are retracted by means which will later be described and the gun is brought into substantial alinement with said plug 120 125 130

members, after which the plug members are projected and the spherical portion 64 caused to seat in the rounded seats 63 of the gun. The water in the gun and the interior of 5 plug members 55 is then withdrawn by pumps through connections 65 and the gates 60 may then be lifted and the interior of the gun will be in communication with chambers 47 and 49 for loading purposes.

10 After the water has been withdrawn from the interior of the gun it will in practice be desirable to dry the interior before loading. This may readily be accomplished by the means illustrated in Fig. 15. As there shown,

15 the pipe branch 165 extends from pipe connections 65 to a compressed air tank 166 within one of the submarine shells. A blast of air delivered from this tank when the gate 60 is closed will drive the moisture

20 ahead of it to the chamber at the muzzle end of the gun, thus effectively drying the interior of the gun. This is desirable because a very considerable amount of water adhering to a gun of the large size contemplated would in

25 evaporating at the time of explosion have a cooling effect, which would tend to reduce the pressure in the gun. In practice, a gun of this character will require a firing chamber of greater diameter than the main bore

30 of the gun, and if this chamber of enlarged diameter were concentric with the bore, it will be apparent that when the gun is horizontal water would collect in the firing chamber which it might be difficult or im-

35 possible to remove. As shown in Fig. 23, the firing chamber 121 is eccentric to the bore 120, and lower walls of both firing chamber and bore being in a common line. This of course enables the gun to be drained 40 and dried as above pointed out without difficulty.

The means for projecting and retracting the plug members 55 is fully shown in Figs. 15 and 16 as applied to the plug members at 45 opposite ends of the gun. A collar 66 is fast on the bushing extension 52. Mounted upon ball bearings on said bushing extension is a ring 67 having thereon a spur gear 68 and a worm gear 69. The spur gear meshes with a 50 pair of spur gears 70, 71 fast on screw shafts 72 which are threaded through balls 73 in casings 74. Formed integrally with plug members 55 are flanges 76 having symmetrically curved outer portions which contact 55 with collars 75.

Lugs 77 on the plug members 55 are back of said ring 75 and slightly spaced therefrom. This permits play and enables the plug member to be moved slightly in longitudinal alinement so that the same may be driven securely into its seat at the end of the gun. The ring 67 is rotated by a worm 78 meshing with worm gear 69 and driven from a motor 79 by a shaft 80.

65 As is best shown in Figs. 13 and 14, the

gun 30 is rigidly secured to trunnion shafts 81, 82 which extend entirely across the submarine shells 25, 26 or 39, 40 and are operated by a worm wheel 83 fast on trunnion 81 meshing with a worm gear 84 on a shaft 85 70 driven from a motor 86. By control means not shown, the gun captain may control the elevation of the gun as desired from indications viewed through the periscopes 87 in any of the forms of submarine here shown. 75

Various means may be employed for loading the gun after the same has been brought into alinement with the loading chambers and the interior sealed in communication with said loading chambers and freed from 80 water. A good form of loading device is shown diagrammatically in Fig. 11 operating for a left-hand load, while the same apparatus is shown more in detail in Fig. 15 85 operating for a right-hand load.

A guide-rest 88 is secured to the interior of chamber 49 (or 47 as shown in Fig. 11), and upon this guide the shell 89 is rested, in which position it will be in axial alinement with the interior of plug 55 and the bore of 90 the gun. A hydraulic ram 90 is horizontally positioned in alinement with the shell and gun barrel, and the ram may be operated by fluid coming from pumps not shown through pipe 91 and front or rear connectors 92, 93 to force the pusher 94 in either direction. When the same is forced outwardly it will engage the edge of the shell and move the shell through the interior of 95 the connector plug 55 and through the interior of the gun. 100

Charges of powder 95 and 96 are held in position at either side of the shell and may be transferred to the guide 88 and forced into the bore of the gun. In order to make 105

firing connection an insulated wire 96 is carried through the trunnion shaft 81 of the gun 30 and along the side thereof, as indicated in Figs. 18 and 15, being held to the wall of the gun by clamps 97. The wire 98 110

within the insulation extends through an insulated plug 99 at the end 62 of the gun, and a ring 100 of insulating material on the inside of the gun end partially encircles the inner side of the ring 100. The last charge 115

of powder 96 embodies a sparking device 101 having one pole connected by plate 102 with the inside wall of the gun and the other pole connected by a coiled wire 103 with a spiral spring 104 in a groove 105 in the outside 120

wall of a cylindrical cap 106, or in place of the spiral spring as shown in Fig. 20 a ring 107 provided with a multiplicity of outstanding flange plates 108 may be placed in the groove 105 as shown in Fig. 21. As the 125

last charge of powder is forced in the wire 103 will uncoil, so that when plug 106 is driven into the end of the gun the coil 104 or the flange plates 108 will engage the exposed portion of wire 109 in insulating ring 130

- 100, thereby completing a circuit which may be placed in communication with any source of electrical energy when it is desired to fire the gun.
5. As clearly indicated in Fig. 23, a disk 122 is inserted in the muzzle of the gun after the same has been loaded to prevent the entrance of water as the gun is being swung through the water to bring its muzzle above the surface. This disk may be of any suitable material provided with frictional means for causing it to remain in the gun and with a slightly flanged portion adapted to seat in the spherical flaring end 63 of the bore to prevent any water pressure from pushing the disk inwardly. Washers 123 of soft pliable material, which will operate to seal the sides of the powder charge so that water cannot pass the same, are secured upon the exposed end of the powder charge 96 which is last put in position. This will prevent any water passing the powder charge and working up in front of the shell, and also will prevent injury of the powder charge when the breech end of the gun is filled with water.
- Under ordinary conditions of use the gun will be carried loaded and in open communication at both ends with the interior of the submarine, that is the interior of the gun freed from water. At a time when it is desirable to fire the gun the gates 60 will be closed, the plug members withdrawn and the gun elevated into firing position by the means described for that purpose. The oscillation of the gun about a vertical axis for training the same will, of course, be effected by the turning of the vessel.
- If for any reason it may be necessary to remove a charge without firing, this may be accomplished by means of an attachment to the hydraulic pusher shown in Fig. 19. This attachment consists of a plunger head 111 secured to a rod 112 which at the other end is provided with another plunger head 113. The plunger head 113 is engaged by the pusher head 94 and moves the charge ahead of it toward the end of the gun. The head 113 is provided with a threaded aperture 114 to which a threaded shank 115 may be connected. This in turn has a head 116 which is again engaged by the plunger head 94. By uniting successive members in this manner all of the charge in the gun may be forced through the same and extruded into the charging chamber at the opposite end.
- It will be understood that in loading the gun the pusher 94 will be employed to position the shell 89 and the successive powder charges 95, 96, and so on, one after the other, in the breech end of the bore of the gun. This, of course, will not put the powder charge and shell in firing position. For moving the combined charge, consisting of the shell and the cases of powder, the gate
- 60 at the breech end of the gun will be closed after the last charge 96 and washer 123 have been positioned in the end of the gun and after the tubular contact piece 106 has been positioned in the breech end of the gun. Water will be pumped into the interior of the plug member 55 under pressure through connections 65. The pressure applied to the water in the chamber of the plug member and the bore of the gun will be sufficient to move the assembled charge to firing position where engagement of the shell with rifling or other checking elements will automatically bring the charge to a stop. In practice the charge will ordinarily be positioned within the gun at the breech end but not forced forward into firing position until the time for firing the gun. It will be apparent that since the breech end of the gun must be filled with water anyway, this method of loading offers no difficulties and will prove particularly convenient and efficient for the purpose. The washer should be hermetically sealed to the exposed end of the last powder case 99 and will engage the inside of the bore of the gun with sufficient friction to prevent any leakage of water past the charge of powder and shell and into the muzzle portion of the gun, either when under the pressure employed when forcing the charge into position or under sea water pressure to which the gun may be exposed by reason of its submergence with the submarine.
- I claim:
1. A submarine war vessel, a gun carried thereby exterior to the submarine, means for loading said gun when below the surface of the water, and means for excluding water from the muzzle of the gun while said muzzle is being raised to the surface of the water, while the submarine remains below the water.
  2. A submarine, and a gun pivotally mounted on a side of the submarine and adapted to be extended upwardly through the water so as to be fired when the submarine is submerged.
  3. A submarine comprising a gun open at both ends and having a bore extending through the same, said gun being pivotally connected adjacent its center to an outside portion of the submarine and being adapted to shoot a projectile from the muzzle end above the water when the submarine is submerged and to shoot an inertia charge of water in the opposite direction thereby rendering the gun recoilless.
  4. A submarine war vessel, and a gun pivotally secured to an outer wall thereof with its axis of oscillation extending through the central horizontal plane of the submarine.
  5. A submarine war vessel, a gun carried thereby exterior to the submarine, means for loading said gun from the interior of the

submarine when said submarine and gun are below the surface of the water, and means for excluding water from the muzzle of the gun while said muzzle is being raised to the 5 surface of the water, the submarine remaining below the water.

6. A submarine war vessel, a gun pivotally connected to a side wall of the submarine and operating outside of the shell 10 thereof, a loading chamber, means for alining the bore of the gun with the loading chamber, and means for opening communication with the loading chamber and sealing the interior of the gun and of said loading 15 chamber from the water.

7. A submarine war vessel comprising a shell having a portion extended from the side and forming a loading chamber, said loading chamber having an aperture at one 20 end and a hollow plug member in said aperture provided with means for closing the same, a gun pivotally connected to a side wall of the submarine and adapted to have its bore brought into alinement with said 25 plug member, and means for operating the plug member to cause the same to enter the bore of the gun and seal the same from the water.

8. A submarine war vessel comprising a shell having a portion extended from the side and forming a loading chamber, said loading chamber having an aperture at one 30 end and a plug member in said aperture provided with means for closing the same, a gun pivotally connected to a side wall of the submarine and adapted to have its bore brought into alinement with said plug member, means for operating the plug member to cause the same to enter the bore of the gun 35 and seal the same from the water, means for withdrawing water from the plug member and gun, and means thereafter for opening the interior of the plug member to the chamber.

45 9. A submarine war vessel comprising a shell having a portion extended from the side and forming a loading chamber, said loading chamber having an aperture at one end and a hollow plug member in said aperture provided with means for closing the same, a gun pivotally connected to a side wall of the submarine and adapted to have its bore brought into alinement with said 50 plug member, the adjacent ends of said gun and plug member having complementary portions for forming a water-tight joint, and means for operating the plug member to cause said members to engage and seal the gun and plug member from the water.

60 10. A submarine war vessel comprising a shell having a portion extended from the side and forming a loading chamber, said loading chamber having an aperture at one end and a hollow plug member in said aperture provided with means for closing the

same, a gun pivotally connected to a side wall of the submarine and adapted to have its bore brought into alinement with said plug member, the adjacent ends of said gun and plug member having complementary portions for forming a water-tight joint, and means for operating the plug member to cause said members to engage and seal the gun and plug member from the water, said 70 plug member and said operating means being mounted to permit lateral movement of the outer end of said plug member to effect registration of the bore of said plug member with the bore of the gun.

11. A submarine war vessel comprising a shell having a loading chamber formed at one side thereof, a gun pivotally connected to a wall of the submarine and adapted to have its bore brought into communication with said loading chamber, and means for 85 sealing the gun and loading chamber from water and for opening communication from the loading chamber to the gun.

12. A submarine war vessel, a gun carried thereby exterior to the submarine, means for effecting communication between the interior of the submarine and the bore of the gun when both are submerged, means for sealing the said communicating gun bore and submarine interior to prevent entrance 95 of water, and means for withdrawing the water from the gun bore.

13. A submarine war vessel, a gun pivotally secured to the outside of a wall thereof with its axis of oscillation extending through 100 the central horizontal plane of the submarine, a pair of extensions from the submarine in the plane of oscillation of the gun, and means for alining the gun with said extensions and for opening communication 105 therewith and sealing the interior of the gun and of such extensions to prevent entrance of the water.

14. A submarine war vessel, a gun carried thereby exterior to the submarine, means for controlling the gun so that the muzzle thereof will extend above the surface of the water when the submarine is submerged, and means for firing the gun when the submarine is submerged.

15. A submarine war vessel comprising a shell having a loading chamber formed at one side thereof, a gun pivotally connected to a wall of the submarine and adapted to have its bore brought into communication with said loading chamber, means for sealing the gun and loading chamber from water and for opening communication from the loading chamber to the gun, and means in the loading chamber for forcing a load into the gun.

16. A submarine war vessel comprising a shell having a loading chamber formed at one side thereof, a gun pivotally connected to a wall of the submarine and adapted to have its bore brought into communication

125

115

120

130

- with said loading chamber, means for sealing the gun and loading chamber from water and for opening communication from the loading chamber to the gun, and a hydraulic ram in the loading chamber for forcing the load into the gun.
17. A submarine comprising a gun open at both ends and having a bore extending through the same, said gun being pivotally connected adjacent its center to an outside portion of the submarine and being adapted to shoot a projectile from the muzzle end above the water when the submarine is submerged and to shoot an inertia charge in the opposite direction thereby rendering the gun recoilless, means for effecting communication between the interior of the submarine and the bore of the gun when both are submerged, and means for forcing a load into the bore of the gun from the breech end thereof when such communication has been established.
18. A submarine war vessel, a gun open at both ends and having a bore extending through the same, a trunnion pivotally connecting said gun near its center of gravity to the submarine, and an electric firing line extending through said trunnion and along the gun to the breech end thereof and through the interior of the gun to the charge for firing the charge.
19. A submarine war vessel comprising a pair of submarine shells held in parallel relation with a space between the same, and a gun pivotally mounted upon said shells and operable within said space.
20. A submarine war vessel comprising a pair of shells, means connecting the shells at the forward and rear portions thereof and forming chambers communicating with the shells, a gun pivotally mounted on the shells and operable between the same and between said connecting members, and means for effecting communication between the interior of said chambers and the bore of the gun.
21. A submarine war vessel, a gun pivotally connected to a side wall of the submarine and operating outside of the shell thereof, a loading chamber, means for placing the interior of the gun in communication with the loading chamber and sealing said interior and said loading chamber from the water, means for placing a charge in the gun, and means for forcing the charge into firing position within the gun.
22. A submarine war vessel, a gun pivotally connected to a side wall of the submarine and operating outside of the shell thereof, a loading chamber, means for placing the interior of the gun in communication with the loading chamber and sealing said interior and said loading chamber from the water, means for placing a charge in the gun, hydraulic means for forcing the charge into

firing position within the gun, and means associated with the charge for effecting a water-tight joint at the back of the charge to prevent water passing through the breech end of the gun and past the charge.

23. A submarine war vessel, a gun carried thereby exterior to the submarine while said submarine is submerged, means for loading the gun when the gun and submarine are submerged, and means for raising the muzzle 75 of the gun above the water and firing said gun while the submarine is submerged.

24. A submarine war vessel, a gun carried thereby exterior to the submarine, means for loading the gun when the gun 80 and submarine are submerged, means for controlling the gun so that the muzzle thereof may be brought from its submerged position, above the surface of the water when the submarine is submerged, and means for 85 sealing the muzzle end of the gun to prevent the entrance of water into the bore of the gun while the gun is being so positioned.

25. A method of loading guns on submarine war vessels, which consists in providing 90 a gun having a bore extending throughout the length of the gun barrel and opening from both ends thereof, providing a pair of chambers with which the ends of the gun are adapted to register, 95 hermetically sealing the connection between the ends of said gun and said chambers, withdrawing the water from the interior of the gun, thereafter opening communication between the chambers and the interior of the 100 gun, positioning the charge in the breech end of the gun, closing communication between the interior of the gun and the breech end chamber, and forcing the charge into 105 firing position by the application of hydraulic pressure back of the charge.

26. A method of loading guns on submarine war vessels, which consists in providing a gun having a bore extending throughout the length of the gun barrel and 110 opening from both ends thereof, providing a pair of chambers with which the ends of the gun are adapted to register, hermetically sealing the connection between the ends of said gun and said chambers, withdrawing 115 the water from the interior of the gun, drying the interior of the gun, positioning the charge in the breech end of the gun, closing communication between the interior of the gun and the breech end of the chamber, and 120 forcing the charge into firing position by the application of hydraulic pressure back of the charge.

27. A submarine war vessel and a gun carried thereby exterior to the submarine, 125 means for effecting communication between the interior of the submarine and the bore of the gun when both are submerged, means for sealing the muzzle end of the gun, and means for controlling the gun so that the 130

muzzle thereof may be brought above the surface of the water from its submerged position.

28. A submarine war vessel, a gun carried thereby exterior to the submarine, means for loading the gun when the gun and submarine are submerged, means for controlling the gun so that the muzzle thereof may be brought from a submerged position to a position above the surface of the water, and means for sealing the muzzle end of the gun to prevent the entrance of water into the bore of the gun.

29. A submarine war vessel, a gun carried thereby exterior to the submarine, means for effecting communication between the interior of a submerged portion of the submarine and the bore of the gun, means for sealing the communicating gun bore and submarine interior to prevent entrance of water, means for withdrawing water from the bore of the gun, and means for drying the interior of the gun bore.

30. A submarine war vessel, a gun carried thereby exterior to the submarine, means for effecting communication between the interior of a submerged portion of the submarine and the bore of the gun, means for sealing the communicating gun bore and submarine interior to prevent entrance of water, means for withdrawing water from the bore of the gun, and means for directing a blast of air through the gun bore for drying the interior surface thereof.

35. 31. A method of loading guns on submarine war vessels, which consists in providing a gun having a bore extending throughout the gun barrel and opening from both ends thereof, providing a pair of chambers with which the ends of the gun are adapted to register, sealing said ends of the gun from outside water pressure, withdrawing the water from the interior of the gun, thereafter opening communication between the chambers and the interior of the gun, positioning the charge in the breech end of the gun, and forcing the charge into firing position within the barrel of the gun, and hermetically sealing the muzzle of the gun against exterior pressure independent of its hermetically sealed connection to the aforementioned chamber.

40. 34. A submarine war vessel, a gun carried thereby exterior to the submarine, means for loading the gun when the gun and submarine are submerged, means for controlling the gun so that the muzzle thereof may be brought from its submerged position above the surface of the water when the submarine is submerged, means for sealing the muzzle end of the gun to prevent the entrance of water into the bore of the gun while the gun is being so positioned, and means for firing the gun.

In testimony whereof I affix my signature in presence of two witnesses.

KENNEDY DOUGAN.

Witnesses:

F. A. WHITELEY.
H. A. BOWMAN.
